JOSEPH H. CHAMP, OF CLEVELAND, OHIO.

MECHANISM FOR FEEDING BOTTLES AND THE LIKE.

1,177,760.

Specification of Letters Patent.

Patented Apr. 4, 1916.

Application filed February 15, 1911. Serial No. 608,787.

To all whom it may concern:

Be it known that I, JOSEPH H. CHAMP, a citizen of the United States, and a resident of Cleveland, county of Cuyahoga, and State of Ohio, have invented a new and useful Improvement in Mechanism for Feeding Bottles and the like, of which the following is a specification, the principle of the invention being herein explained and the best mode 10 in which I have contemplated applying that principle, so as to distinguish it from other inventions.

In connection with bottle filling machines of the continuous rotating type, such as 15 illustrated in my Patent No. 956,285, dated April 26, 1910, it has for some time been the practice to utilize automatic bottle receiving devices, whereby the filled bottles are automatically removed from the successive 20 holders of the machine as they are brought around to the discharge station. Owing, however, to a variety of difficulties it has heretofore been found impossible to devise means capable of similarly automatically 25 feeding the bottles to such machine, for obviously such feeding operation must not only synchronize with the rotative movement of the machine, but must also be responsive to varying conditions that may 30 exist in the bottle holders, so as not to force a bottle onto the machine where not fitted to receive it through some accident or improper location of parts. By the present invention these several difficulties are overcome, and a mechanism is provided that is 35 capable of thus automatically feeding the bottles onto the successive holders of the machine, as also one that is adjustable to accommodate different sizes of bottles such 40 as may be filled with the machine at different times.

To the accomplishment of these and related ends, the invention, then, consists of the means hereinafter fully described and 45 particularly pointed out in the claims.

The annexed drawings and the following description set forth in detail certain mechanism embodying the invention, such disclosed means constituting, however, but one 50 of various mechanical forms in which the principle of the invention may be used.

In said annexed drawings:—Figure 1 is a plan view of my improved bottle feeding mechanism in proper relation to that portion of the filling machine wherewith it operates; Fig. 2 is partly a side elevational

view of the same, and partly a section on the line 2—2, Fig. 1; Figs. 3, 4 and 5 respectively illustrate, in different operative positions, certain details of the mechanism; 60 and Fig. 6 shows a modification.

Only so much of the filling machine proper is shown in said figures as is necessary to illustrate the relation thereto of the bottle feeding apparatus; and while the machine thus selected for illustrative purposes is the machine of the patent previously named, it will, of course, be understood that the present mechanism may be employed in conjunction with any machine of the same 70 general type, viz. characterized by having a plurality of conjointly movable bottle holders, or lifts, on which the bottles require to be placed during the filling operation. The portion of the machine thus illustrated then, comprises a series of bottle holders, or lifts 1, as they may be variously termed, depending on the mode of operation of the machine, which holders serve to carry the bottle 2 from the receiving station to the 75 discharging station. The only portion of the rotary carrier for supporting said rests that appears in the figures is the series of radial arms 3, while none of the filling mechanism, proper, at all is shown. 85

The mechanism of present interest is supported upon a horizontal plate, or table 4, suitably secured to the machine fram 5 at an elevation such that the upper surface of said table is on substantially the same plane 90 as the holders 1 of the filling machine whereon the bottles require to be placed. Said table in the illustrated constructional form is located in close proximity to the bottle receiving apparatus 6 whereby the 95 filled bottles are removed from the machine. This apparatus however, forms no part of the present invention and hence need not be further described.

Extending longitudinally of table 4, or in 100 other words, in a more or less tangential direction relatively to the circular path of travel of the bottle holders 1 is an endless belt 7, the upper lap of which is substantially flush with the top of the table and 105 serves as a conveyer, whereby the bottles placed thereon by the operator are moved up into a position directly adjacent to the bottle holders as they pass. Said belt may be driven through any suitable mechanism 110 as a chain 8 and sprocket 9, either from some rotating part of the filling machine, or

independently; for as will presently appear, it is not essential that the rate of movement of the belt and that of the machine should be correlated; the only requirement being that the bottles be brought up at least as fast as is necessary to supply successive holders of said machine. The bottles are held in line as they are thus conveyed to the feeding station by said conveyer belt, and at the same time are prevented from being crowded off from the latter, by means of guides 10 and 11, one on each side of said belt. The guide 10 on the inner side is preferably straight throughout and pivotally secured to the supporting plate by a pin 12 and is capable of a certain amount of oscillation about such pin, although normally held in substantial alinement with the edge of the belt by a spring 13 attached to the side of the guide and held between studs 33 on the upper face of said plate. The guide 11 on the outer side on the contrary has its inner end, that is the one at the discharge end of the belt, extend beyond that of the inner guide and curved so as to direct the endmost bottle off the belt and onto a bottle holder when stationed adjacent to this point. Said outer guide is attached to the plate by means of two laterally projecting, slotted ears 14 through which set bolts 15 are adapted to pass, whereby said guide may be adjusted transversely of the belt to permit the passage between it and the other guide of bottles of different sizes.

35 Operation of the mechanism, whereby the bottles are singly placed onto successive holders, is controlled independently of the conveyer just described and directly by the holders themselves. This mechanism comprises a gate in the form of a pivotal member 16 with two angularly related radially extending arms 17 and 18 against the latter of which, in the normal position of said gate, the innermost bottle of the series resting on the conveyer is caught so as to block its further advance. (See Fig. 4).

50 The gate arm 17 extends beyond the edge of the table and into the path of the holders 1 so that the latter are adapted to successively engage therewith and swing the gate into the position shown in Fig. 3. The endmost bottle in this position is free to slide off the belt and intervening section of the table onto the holder, which has thus actuated the gate, the bottle being induced to do this by reason of the pressure of the following bottles against it. This movement need not effect immediately a complete transfer of the bottle thus shoved out of line, as it were, but as the holder moves onward, it sweeps such bottle along with it and the combined wedging effect of the next succeeding bottle, together with that of a resilient guide or finger 19 disposed so as to intersect at a slight angle the path of the holders, as

shown in the several figures, is to place the bottle as far back on the holder as it is adapted to go.

The action of the gate 17 can be seen clearly in Figs. 3, 4 and 5. In Fig. 3 the can B is held against movement back onto the conveyer by the can C. The movement of the holder next swings the gate 16 in a counter-clockwise direction, when the arm 18 will be moved out of the way of the can C. The latter is then operated by the conveyer to force the can B onto the holder as shown in Fig. 3. The can B is not fully on the holder but is moved farther onto the same by the spring 19, upon continued rotation of the holder assisted by the can C which is moved along the arm 18 of the gate. The holder is of course provided with a raised rim or lateral flange 20 of the proper conformation to thus receive said bottle and locate the same centrally with respect to the filling mechanism (not shown) wherewith it is intended to subsequently co-operate. As soon as a bottle has been thus moved out of the way, the gate 16 is swung back into its normal position by the operation of a tension spring 21, which is connected with an arm 22 attached to the gate for this purpose, such spring lying against the outside face of the guide 11, shown in Fig. 4. An intermediate position of the parts is illustrated in Fig. 5. The advance of the line of bottles is now again stopped until another holder engages the arm 17 of the gate. Thereupon the operation just described is repeated and so on, as long as the machine is rotated and bottles are supplied to the conveyer.

From the foregoing description of the construction and operation of the machine, it will be seen that the feeding of the bottles onto the holders is not only entirely automatic, but is strictly controlled by the holders as they successively present themselves to receive said bottles. There can, accordingly, be no interruption of the feeding operation so long as bottles are supplied to the conveyer, nor on the other hand, will the stopping of the machine, or the disarrangement of any particular holder thereof, lead to the breaking of bottles; since under such circumstances the feeding operation is immediately suspended, to be resumed, however, the moment a holder is presented in proper condition.

It will, of course, be understood that no limitation is implied by the reference herein to the use of my improvements to feed bottles onto a bottle-filling machine; for obviously such improved mechanism is equally adapted for the feeding of other containers, such as cans, onto a can-filling machine; or, in fact, for feeding objects of equivalent character onto the successive holders of any similarly movable receiving mechanism.

Also, as illustrated in Fig. 6, it is not necessary for the conveyer to extend right up to the point where the bottles are transferred onto the successive holders; but the pressure of those bottles, which follow behind, upon those going before may be relied on if desired to advance said bottles through the whole of the distances marked off by guides 10 and 11. In such case, the bottles simply slide along the smooth top of plate 4. This arrangement is of practical advantage when a conveyer, as an endless belt 23 in the figure last referred to, is employed to bring the bottles up to the feeding mechanism.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism for feeding bottles or the like onto a series of conjointly movable holders, the combination with bottle feeding mechanism comprising an endless conveyer disposed adjacent to such holders, of spaced guides alined with said conveyer, having discharge ends adjacent to such holders and the inner of said guides being oscillatory in the plane of said conveyer, and a resilient finger carried by said inner guide and extending into the path of such holders and adapted to transfer thereto a bottle discharged from between said guides.

2. In mechanism for feeding bottles or the like onto a series of conjointly movable holders, the combination with bottle feeding mechanism comprising an endless conveyer disposed adjacent to such holders, of spaced guides alined with said conveyer, having discharge ends adjacent to such holders and the

inner of said guides being oscillatory in the plane of said conveyer, and a gate normally restraining the transfer of bottles from between said guides to such holders, said gate being adapted to be rendered inoperative by such holders.

3. In mechanism for feeding bottles or the like onto a series of conjointly movable holders, the combination with bottle feeding mechanism comprising an endless conveyer disposed adjacent to such holders, of spaced guides alined with said conveyer, having discharge ends adjacent to such holders and the inner of said guides being oscillatory in the plane of said conveyer, and a resilient finger carried by said inner guide and extending into the path of such holders and adapted to transfer thereto a bottle discharged from between said guides; and a gate normally restraining such transfer, and being adapted to be rendered inoperative by such holders.

4. In mechanism for feeding bottles or the like onto a series of conjointly movable holders, the combination with bottle feeding mechanism comprising an endless conveyer disposed adjacent to such holders, of spaced guides alined with said conveyer, having discharge ends adjacent to such holders and the inner of said guides being oscillatory in the plane of said conveyer; a pivotal gate having an arm adapted to restrain such transfer of bottles from between said guides to such holders; and means normally thus positioning said gate; said gate being adapted to be engaged and swung into inoperative position by respective holders.

Signed by me this 10th day of February, 80
1911.

JOSEPH H. CHAMP.
